UNITED STATES PATENT OFFICE.

WILLIAM G. BECKWITH, OF PRATTVILLE, ALABAMA.

JOURNAL-BOX.

SPECIFICATION forming part of Letters Patent No. 560,565, dated May 19, 1896.

Application filed July 15, 1895. Serial No. 556,026. (No model.)

To all whom it may concern:

Be it known that I, WILLIAM G. BECKWITH, a citizen of the United States, residing at Prattville, in the county of Autauga and State of Alabama, have invented certain new and useful Improvements in Journal-Boxes; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention contemplates certain new and useful improvements in journal-boxes, and relates more particularly to that class known as "oscillating."

The object of the invention is to provide a device of this character which will be simple in construction and efficient in operation, one which may be easily set up or taken down, and one in which simple and efficient means are provided for lubricating the shaft supported by said journal-box.

In carrying out my invention I form a bed or base plate of two parts or sections, each of which is provided with a bearing for the reception of trunnions extending transversely from the journal box or bearing proper. This latter is also composed of two parts or sections, which form an interior chamber, in which is designed to fit a sleeve or lining of any suitable antifrictional metal. This sleeve is also preferably formed in two parts or sections, and the upper section is provided with grooves in its top surface and a lug or projection extending up into an oil-reservoir formed in the upper section of the journal-box. The oil-reservoir is provided with suitable outlet holes or openings, which register with grooves or recesses formed in said interior chamber and leading to the bottom thereof, where a supplemental reservoir is formed. The lower section of the antifrictional sleeve is provided with a longitudinal slot, in which fits a strip of wool or felt or other similar substance, which will convey lubricant by capillary attraction from said supplemental oil-reservoir to the shaft supported by said journal-box.

The invention will be hereinafter more fully

set forth, and particularly pointed out in the claims.

In the accompanying drawings, Figure 1 is 55 a view in side elevation. Fig. 2 is a cross-sectional view on the line $x-x$, Fig. 1. Fig. 3 is a plan view with the top sections removed. Fig. 4 is a bottom plan view of the top section of the journal-box. Fig. 5 is a detail 60 view; and Fig. 6 is a sectional detail view on line $y-y$, Fig. 1, the base-plate being removed.

Referring to the drawings, A designates the bed or base plate, which is formed in two parts or sections a a' , which are designed to 65 be united together at a^2 by means of suitable screws or bolts, said sections being provided with holes or openings a^4 for the accommodation of securing-bolts (not shown) used in mounting said bed or base plate into position. 70

The journal box or bearing proper is formed in two parts or sections b b' , united together by nutted bolts b^2 , the heads of which fit in suitable grooves or recesses in bed or base plate A and corresponding recesses in the 75 section b . From the lower section b project transverse trunnions b^3 , which are pivotally supported in bearings b^4 , extending upwardly, one from each of the parts or sections a a' of said bed or base plate. The interior of the 80 sections b and b' is hollowed out to form a cylindrical chamber b^5 , having end walls b^6 , said chamber being designed to accommodate a bearing-sleeve C, formed in two parts or sections C C' of semicircular form in cross-section. This sleeve is made from any suitable antifrictional metal, preferably Babbitt metal. 85

D is an oil-reservoir located in the upper portion of section b' of the journal-box, feed 90 holes or openings d and d' being formed in the bottom of said reservoir. The opening d registers with a groove or recess d^2 in the inner surface of the section b' , which groove in turn registers with a similar groove d^3 in 95 section b , which with a groove d^4 in section C' forms a conduit for the oil. The opening d' registers with a groove d^4 in the top surface of the section C' of the antifrictional sleeve, and this groove in turn registers with 100 a second groove d^5 in section b , communicating with a groove d^6 of section b . (See Fig. 6.) The grooves d^3 and d^6 are connected by a groove d^7 , forming a supplemental oil-

reservoir, in which is designed to rest a strip of wool or felt d^8 , which is projected through a slot d^9 of the section C^2 of sleeve C. By means of this piece of wool or felt a gradual feed of oil to the shaft X is maintained by capillary attraction. While I have specified wool or felt for this purpose, I do not limit myself thereto, as any suitable fibrous substance may be employed without departing 10 from the spirit of my invention.

The section C' of sleeve C is provided with a lug or projection e , which extends through a hole or opening e' of section b' into the oil-reservoir D, the section of said sleeve being 15 thereby prevented from revolving with the shaft X, mounted in said sleeve. The section C^2 is provided with a lug e^2 , fitting in a recess e^3 of the section b . The amount of longitudinal play of shaft X in its bearings is regulated by an adjusting-screw E, mounted in a cylindrical portion e^4 of the section b . (See Figs. 1 and 3.) The oil-reservoir D is provided with a suitable cover e^5 , pivoted at e^6 to lugs e^7 of the reservoir.

25 The advantages of my invention are apparent to those skilled in the art to which it appertains, and it will be readily seen that because of the bed or base plate being formed in two parts or sections the same may be 30 easily mounted, and its accurate working and ease of adjustment will be thereby insured. It will also be seen that the piece of wool or felt will effect a gradual and efficient lubrication and at the same time prevent any grit 35 or foreign substance from reaching the interior or bearing-surface. It is clear also that the antifrictional sleeve C may be easily replaced when worn.

I claim as my invention—

40 1. The herein-described journal-box, comprising a bed or base plate formed in two separable parts or sections, bearings formed on said sections, a journal-bearing formed in sections and having trunnions supported by 45 said former bearings, and an antifrictional sleeve or lining within said journal-bearing, grooves or conduits for lubricant being formed in the sections of said journal-bearing and also in said sleeve or lining, as set forth.

50 2. The herein-described journal-box, comprising a bed or base plate formed in two separable parts or sections, bearings formed on said sections, a journal-bearing pivotally supported by said bearings and having an interior chamber, and an antifrictional sleeve or 55 lining fitting within said chamber, grooves or conduits for lubricant being formed in the inner surface of said chamber and also in the outer surface of said sleeve or lining as set 60 forth.

3. The herein-described journal-box, comprising a box or bearing formed in two parts or sections and having an interior chamber, a sleeve or lining of antifrictional metal fitting within said chamber, an oil-reservoir 65 mounted on the top of said box or bearing, said sleeve or lining and said chamber having

grooves or recesses leading from said oil-reservoir to the bottom of said chamber, and means communicating with said grooves or 70 recesses for feeding lubricant to the interior of said sleeve or lining, as set forth.

4. The herein-described journal-box, comprising a box or bearing formed in two parts or sections and having an interior chamber, 75 a sleeve or lining of antifrictional metal fitting within said chamber, an oil-reservoir mounted on the top of said box or bearing, a supplemental reservoir located in the bottom of said chamber, said sleeve or lining and said 80 chamber having grooves or recesses leading from said main reservoir to said supplemental reservoir, and means for feeding lubricant from said supplemental reservoir to the interior of said sleeve, substantially as set forth. 85

5. The herein-described journal-box, comprising a box or bearing formed in two parts or sections and having an interior chamber, a sleeve or lining of antifrictional metal fitting within said chamber and provided with 90 a lower longitudinal slot or opening, a main oil-reservoir mounted on the top of said box or bearing, a supplemental reservoir located in the bottom of said chamber, said sleeve or lining and said chamber having grooves or 95 recesses leading from said main reservoir to said supplemental reservoir, and a strip of wool or felt located in said supplemental reservoir and projected up through the slot or opening of said sleeve or lining, substantially 100 as set forth.

6. The herein-described journal-box, comprising a box or bearing formed in two parts or sections and having an interior chamber, a sleeve or lining of antifrictional metal fitting within said chamber and provided with 105 a lower longitudinal slot or opening, a main oil-reservoir mounted on the top of said box or bearing and having holes or openings in its bottom, a supplemental reservoir located in 110 the bottom of said chamber, said sleeve or lining and said chamber having grooves or recesses registering with the holes or openings in said main reservoir and leading to said supplemental reservoir, and a strip of wool or 115 felt located in said supplemental reservoir and projected up through the slot or opening of said sleeve or lining, substantially as set forth.

7. In a journal-box, a sleeve or lining of antifrictional metal formed in two parts or sections, one of said sections having a slot or opening therein, a supplemental oil-reservoir located adjacent said slot or opening, a main reservoir, said reservoirs having communication with each other and a strip of felt located 125 in said reservoir and projected through said slot or opening, substantially as and for the purpose set forth.

8. The herein-described journal-box, comprising a box or bearing formed in two parts 130 or sections and having an interior chamber, a sleeve or lining of antifrictional metal located within said chamber, said sleeve being also formed of two parts or sections, an oil-

reservoir mounted on the top of said box or bearing, a lug or projection secured to the upper section of said sleeve or lining and extending into said reservoir, said sleeve or lining and said chamber having grooves or recesses leading from said reservoir to the bottom of said chamber, and means for feeding lubricant to the interior of said sleeve or lining, as set forth.

10 9. The herein-described journal-box, comprising a bed or base plate formed in two parts or sections, bearings formed on said sections, a journal-bearing pivotally supported by said bearings and having an interior chamber, an antifrictional sleeve or lining secured in said chamber, and an adjusting-screw projecting into said chamber, as set forth.

15 10. The herein-described journal-box, comprising a box or bearing formed in two parts or sections and having an interior chamber, a sleeve or lining of antifrictional metal located within said chamber, said sleeve being

also formed in two sections and provided with a slot or opening, a main oil-reservoir mounted on the top of said box or bearing provided 25 with feed holes or openings in its bottom, a lug or projection secured to the upper section of said sleeve or lining and projecting into said oil-reservoir, a supplemental reservoir located in the bottom of said chamber, said 30 sleeve or lining and said chamber having grooves or recesses registering with said feed holes or openings and leading to said supplemental reservoir, and a strip of wool or felt located in said supplemental reservoir and 35 projected up through the slot or opening of said sleeve or lining, substantially as set forth.

In testimony whereof I affix my signature in presence of two witnesses.

WILLIAM G. BECKWITH.
